Primary Examiner — Sheryl Lane*Assistant Examiner* — Samantha N Wood(74) *Attorney, Agent, or Firm* — Nirav D. Parikh; Edgar A. Zarins**CLAIM**

The ornamental design for a spout, as shown and described.

DESCRIPTION

FIG. 1 is a front perspective view of a spout showing my new design;

FIG. 2 is a rear perspective view thereof;

FIG. 3 is a front elevational view thereof;

FIG. 4 is a left side view thereof;

FIG. 5 is a rear view thereof;

FIG. 6 is a right side view thereof;

FIG. 7 is a top plan view thereof; and,

FIG. 8 is a bottom view thereof.

The broken lines are included for the purpose of portions of the article and form no part of the claimed design.

1 Claim, 4 Drawing Sheets(56)
